UNITED STATES PATENT OFFICE.

KARL G. KARSTEN, OF NEW YORK, N. Y.

INFORMATION-DISPENSING SET.

Application filed February 19, 1920, Serial No. 359,914. Renewed October 22, 1924.

To all whom it may concern:

Be it known that I, KARL G. KARSTEN, a citizen of the United States, and resident of New York, in the county of New York and State of New York, have invented certain new and useful Improvements in Information-Dispensing Sets, of which the following is a specification.

The invention relates to an article of commerce designed to constitute one set of a series of such sets for use in a method of distributing and recording information, such as new items or the information which is usually supplied by clipping bureaus and the like.

One of the objects of the invention is to provide a conveniently handled instrumentality for supplying information in such a way that there will be featured a service which may be regarded as the equivalent of a daily newspaper or bulletin service on sheets hereinafter identified as master sheets, and coacting therewith a permanent record of the information in forms available to constitute part of a card-index system and identified hereinafter as cards.

The invention contemplates the coactive operation of the two sets of writings with each set designed to fulfill a peculiar requirement of the service supplied and coacting to complete all requisites of the service.

Still another object of the invention, incidental to the general desideratum to provide efficiency in handling and distributing the information, is to provide the card feature in a set comprising a plurality of similar cards differing from each other in the positioning of a permanently displayed sub-title within range of the card filer's vision and with the sub-title printed in some distinctive type or contrasting colored ink differing from the other matter duplicated on the body of the several cards in the initial printing of the cards.

Still another object of the invention in connection with the master sheet, daily digest or newspaper sheet is to provide a character of sheet in which the type is open so as to be readily read and which sheet can be assembled in a suitable carrier with other similar sheets for circulation about an office or plant and then destroyed if desired.

Various other objects and advantages of the invention will be in part obvious from an inspection of the accompanying draw-

ings and in part will be more fully set forth in the following particular description of one form of card system embodying my invention, and the invention also consists in certain new and novel features of arrangement and combination of parts hereinafter set forth and claimed.

In the accompanying drawings:—

There is illustrated largely in diagrammatic form one set of the parts which go to make up the article constituting the subject matter of this application and which is designed to represent a plurality of such sets differing from each other in the subject matter of the text on the different sets and in the number of cards which constitute the card feature of the disclosure.

In the drawings:

Figure 1 is a face view of one of the temporary elements of the set previously identified as the master sheet or daily digest sheet.

Figures 2, 3 and 4 are face views of the card elements of the organization all of the cards being identical in their original printing except for the sub-titles; Figures 2 and 3 illustrating different sub-titles and Figure 4 illustrating the duplication of a main title and its utilization as a sub-title.

In the following description and in the claims, parts will be identified by specific names for convenience of expression but they are intended to be as generic in their application to similar parts as the art will permit.

In the drawings and referring first to the master sheet, shown in Figure 1, there is disclosed a relatively large sheet 10, provided along one edge with assembling apertures, 11 for assembling the sheets in a temporary binder or suitable carrying or filing device.

These sheets are originally provided with certain printed matter thereon, such as a heading 12, a designation of office routing 13, and a librarian notice 14, and a heading 15 of subjects covered. The major portion of the sheet is blank, and this blank space is designed to be printed or typed with the information and other data which it is desired to place on the different master sheets. It will be understood that one master sheet is prepared and duplicated so that each subscriber gets one or more of these sheets.

The completed sheet when prepared ready for distribution includes the text 16 which it is desired to distribute and file, together with a main classification title 17. In one com-

mercial form of this device, the main classification title is the name of the author of the news or information, the magazine or other source from which the text is taken and a general classification title, such as a brief heading of the article covered by the text.

Under the heading of subjects covered are listed certain short sub-titles 18 which are of assistance in indicating to the classifier the proper routing of the daily sheets through the office or plant of the subscriber.

It is understood that this master sheet is not intended for permanent record and is run off by the printer or typewriter usually 15 on a cheap grade of paper and is intended to be thrown away when it has completed its route through the office. As this sheet is designed for ready and rapid reading, the type used is relatively large and the 20 paragraphs and sentences are well spaced and the different parts are otherwise arranged to take advantage of the usual printing practices for getting up a readily readable sheet. The sheet is provided with sufficient spaces thereon to permit the insertion of any notes by the readers as the sheet 25 is being routed through the office.

The auxiliary cards shown in Figures 2, 30 3 and 4 are more pretentious in their appearance, are of good grade of material to insure a permanent record, and are of one of the standard sizes now used in card-index systems.

Each of the cards is provided with a writing 35 thereon and all of the cards, with the exception of the sub-title hereinafter described, are all printed alike originally so as to form duplicates of each other. In other words, the three cards shown in the 40 drawings are struck off at the same time and as many duplicates are printed as there are card indexes to be supplied.

The cards include a paragraph usually in 45 very small type which is a duplicate of the textual matter 16 upon the master sheets.

The cards differ from each other in the inclusion of one of the sub-titles 18 which is displayed in key position at the upper 50 edge of the cards to constitute a main title for the card and which title is designated by the reference character 20 on the cards shown in Figures 2, 3 and 4, one card for each of the sub-titles listed on the daily digest sheet.

The efficiency of the librarian in filing 55 these cards is very much enhanced by making the sub-titles with a prominently displayed notice impelling writing. This writing is most readily provided by making the sub-titles in an ink differing in color from the ink on the body of the cards. It has been found that the printing or the writing 60 of the card in black ink and the printing or typing of the sub-title in red ink has proven highly satisfactory. It will be no-

ticed in referring to Figures 2 and 3 that they have different sub-titles but in Figure 4 the sub-title is the same as the originally printed main title except that it is in colored ink as previously described.

While I have shown and described, and have pointed out in the annexed claims, certain novel features of my invention, it will be understood that various omissions, substitutions and changes in the form and details of the card system illustrated and in its operation may be made by those skilled in the art without departing from the spirit of the invention.

Having thus described my invention, I 80 claim:

1. An article to be used in a method of distributing and filing information, including a temporary sheet or newspaper constituting a daily digest sheet designed to be thrown away when read, said sheet provided with a writing thereon and which writing includes a text of the information distributed, a main classification title and a plurality of sub-titles, a plurality of permanent cards, one for each sub-title on the daily digest sheet, each card having certain writing thereon, being each a duplicate of the writing on every other card, said writings including the text of the information 95 distributed, a main classification title, and which cards differ from each other in that each card has prominently displayed along the upper edge thereof the text of one of the sub-titles on 100 the daily digest sheet, said cards and sheet adapted to be assembled for mailing as a unit.

2. An article to be used in a method of distributing and filing information, including a temporary sheet, said sheet provided with a writing thereon and which writing includes a text of the information distributed, and a plurality of titles, a plurality of permanent cards, each card having certain writing thereon, being each a duplicate of the writing on every other card, said writings including the text of the information on the daily digest sheet and which cards differ from each other in that each card has prominently displayed along an edge thereof the text of one of the titles on the temporary digest sheet, said titles on the cards being in a differently colored ink from the other writings on the card to facilitate the filing of the cards in the card index system.

3. An article of manufacture for distributing and recording information, comprising a set of one master sheet designed for temporary use, and a plurality of auxiliary cards designed to constitute part of a card index system, said master sheet having a writing thereon designed to effect a rapid display of information and the auxiliary cards having two writings thereon, one con- 125 130

stituting a repetition of the text of the information on the master sheet and the other designed to effect the rapid filing of the information in a card index system, the set 5 being linked together into a complete article by the use of similar sub-titles appearing prominently displayed in key-position and

color collectively upon the master sheet and singly upon each of the auxiliary cards.

Signed at New York city, in the county of ¹⁰ New York and State of New York, this 5th day of February, A. D. 1920.

KARL G. KARSTEN.
